UNITED STATES PATENT OFFICE.

RAY S. MATTINGLEY, OF ROCKPORT, INDIANA.

SINGLETREE.

1,411,501.

Specification of Letters Patent.

Patented Apr. 4, 1922.

Application filed July 7, 1921. Serial No. 483,040.

To all whom it may concern:

Be it known that I, RAY S. MATTINGLEY, a citizen of the United States, and a resident of Rockport, in the county of Spencer and 5 State of Indiana, have invented certain new and useful Improvements in Singletrees, of which the following is a specification.

This invention relates to a singletree and more particularly to the construction 10 thereof.

The object of the invention is to provide a single tree of such construction that the same will be light and durable and adapted to withstand a great pulling strain without 15 breaking.

It is also an object of the invention that the structural features employed shall be adapted to be utilized in the construction of a doubletree or neck-yoke.

20 Other objects will hereinafter appear in the detailed description to follow.

The invention is illustrated by way of example in the accompanying drawings, in which:—

25 Figure 1 is a perspective view of a single-tree constructed in accordance with the present invention,

Figure 2 is a transverse section taken through the longitudinal center of the same,

30 Figure 3 is a fragmentary sectional view illustrating the manner in which the trace hooks are connected to the single-tree,

Figure 4 is a longitudinal sectional view illustrating the structural elements of the 35 singletree before the same are riveted together,

Figure 5 is a perspective view of a neck-yoke in which the structural features of the present invention have been incorporated.

40 Referring to the drawings more particularly, 10 indicates a filler strip which is of wood, or the like, and the thickness thereof tapering or decreasing toward its ends from the longitudinal center thereof as best shown 45 in Figure 4. A metal strip 11 is placed upon each side of the filler strip 10, said strips 11 being greater in length than the filler strip 10 and having the extended end portions 12. In constructing the singletree the metal 50 strips 11 are positioned upon each side of the filler 10, as shown in Figure 4, and the metal strips and filler are then rigidly secured together by means of rivets 13, each of the rivets extending through both metal strips and 55 filler strip.

It is of course to be understood that suitable openings are made in the strips 11 and filler 10 for receiving the rivets as shown at 14, in Figure 4. In riveting the strips upon the filler the ends thereof must be sprung 60 downwardly due to the tapering sides of the filler and in so doing a solid and durable structure is formed, the tension of the metal strips add to the strength of the singletree as a whole in a manner well understood. Also 65 as is apparent the tension of the metal strips eliminates any possibility of the rivets loosening and generally increases the durability of the singletree.

Between each of the corresponding ends 70 12 of the metal strips there is pivoted a trace hook 15 by the means of a rivet 16. The hooks 15 are adapted to receive a trace link as at 17 and their free ends are caused to press against the forward edge of the filler 10 75 when a pulling strain is applied upon the hooks as shown in Figures 1 and 3, the purpose of this is to hold the trace chains against accidental removal.

It will be observed that the longitudinal 80 edges of the filler plate 10 slightly extend from the similar edges of the strips 11, the purpose of this is to eliminate any possibility of the horse's legs coming in contact with the edges of the metal strips 11. 85

At the longitudinal center of the singletree and adjacent the forward edge thereof a suitable opening is provided for receiving a pin 19, by which the free ends of a clevis 20 may be secured to the singletree. The 90 clevis 20 may be of any desirable construction and the pin 19 is preferably formed with a head at each end in order to eliminate accidental removal or displacement.

It is believed from the foregoing description that the advantages of the present invention may be clearly understood.

It may be here mentioned that a doubletree may be constructed in a similar manner providing the strength of the material used 100 is proportionally increased.

Referring to Figure 5 in which a neck-yoke constructed in accordance with the present invention is exemplified, 22 indicates the reinforcing metal strips which correspond 105 to the metal strips 11 shown and described in Figures 1 to 4. Between the strips there is of course positioned a filler such as shown by the reference numeral 10 in Figures 1 to 4 and the same general features of construc- 110

tion relative to the tapering of the filler toward its ends are included. Also a ring 22 is positioned in the extended ends of the metal strips 21 and a suitable clevis 23 is riveted at an intermediate point of the ends of the neck-yoke as shown, said clevis supporting a ring 24.

I claim:

1. A singletree construction comprising a pair of metal strips, a filler therebetween, the thickness of which decreases or tapers toward its ends from its longitudinal center, rivets extending through said strips and filler by which they are secured together to form a solid structural unit, the ends of said strips slightly extending beyond the corre-

sponding ends of the filler, a trace hook having its one end pivotally connected between each of similar extended ends of said metal strips, and a clevis secured to the singletree 20 at a point intermediate its ends.

2. A draft element construction of the character specified comprising a filler, the thickness of which decreases or tapers toward its ends, a spring metal strip upon a pair of opposing sides of the filler extending longitudinally thereof and sprung against the tapering portions of the filler, and means extending through said strips and filler for rigidly securing the strips together and against the associated sides of the filler.

RAY S. MATTINGLEY.
